VENT FOR BACK GUARD RAILS OF STOVES

Robert J. Merritt, Los Angeles, Calif.

Application March 21, 1949, Serial No. 1,508

Term of patent 3½ years

(Cl. D81—25)

To all whom it may concern:

Be it known that I, Robert J. Merritt, a citizen of the United States, residing in the city of Los Angeles, county of Los Angeles, State of California, have invented a new, original, and ornamental Design for a Vent for Back Guard Rails of Stoves, of which the following is a specification, reference being had to the accompanying drawings, forming a part thereof.

Fig. 1 is a perspective view of the vent for back guard rails of stoves, showing my new design, being a front view taken from the top and one end thereof. Fig. 2 is an enlarged perspective view of the vent for guard rails of stoves, being a rear view taken from the top and the other end

thereof, and Fig. 3 is an end view of the vent for guard rails of stoves.

I claim:

The ornamental design for a vent for back guard rails of stoves, as shown.

ROBERT J. MERRITT.
